UNITED STATES PATENT OFFICE

CHARLES F. LEE, OF PHILADELPHIA, PENNSYLVANIA, ASSIGNOR OF ONE-HALF TO
WARREN P. GRIFFITHS, OF PHILADELPHIA, PENNSYLVANIA

MEANS FOR PRODUCING COMBINED WOVEN AND KNITTED FABRICS

Application filed March 19, 1930. Serial No. 437,095.

This invention relates to new and useful improvement in means for producing a combined woven and knitted fabric and more particularly to a device of this character which is adapted to produce a fabric having a knitted face side while the other side of said fabric is woven.

An important object of this invention is to provide, in a manner as hereinafter set forth, a device of the aforementioned character which is adapted to produce a piece of fabric or cloth having one side knitted and the opposite side woven either in various designs or plain as desired, and wherein this is accomplished without the necessity of using any additional material other than that which is required for producing a piece of fabric or cloth wherein both sides are woven.

Another very important object of the invention is to provide, in a manner as herein-after set forth, means for producing a combined woven and knitted fabric which is adapted to be expeditiously mounted on or removed from looms of conventional construction which are already in use without the necessity of materially altering the said loom and whereby said loom may be used to produce a fabric which is woven on both sides in the usual manner when the device constituting this invention is removed therefrom.

Another important object of the invention is to provide a means for producing a combined woven and knitted fabric wherein the fabric or cloth produced thereby will not stretch or pull out of its woven shape and the invention aims still further to provide a device of this character which is adapted to operate on any kind of fabric or cloth.

A still further important object of the invention is to provide a device of the character set forth which is adapted to knit certain of the weft threads which are left by a shuttle of a loom to which the invention is operatively attached.

Still further objects of the invention are to provide in a manner as hereinafter set forth, means for producing a combined woven and knitted fabric of the character described which will be simple in construction, strong,

durable, efficient in its use and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is a view in front elevation showing a portion of a conventional loom with the device constituting this invention mounted in operative position thereon.

Figure 2 is a top plan view thereof.

Figure 3 is a view in elevation looking at one end of a portion of a loom with the device mounted thereon.

Figure 4 is a view in elevation looking at the opposite end of the loom with the device mounted thereon from the end illustrated in Figure 3.

Figure 5 is a detail view in section showing the knitting needle supporting means with the needles mounted in position therein and the actuating mechanism therefor, said needles being shown in extended or projected position.

Figure 6 is a view similar to Figure 5 with the knitting needles in retracted position.

Figure 7 is an enlarged fragmentary detail view in longitudinal section taken through the bed plate in which the knitting needles are mounted.

Figure 8 is a fragmentary detail view in top plan showing one end portion of the needle supporting bed plate.

Figure 9 is a fragmentary detail view in perspective showing the cam engaging end portion of the bed plate rocking arm.

Figure 10 is a perspective view illustrating certain elements forming a part of the invention which are engaged with the opposite ends of the bed plate.

Figure 11 is an enlarged plan view of a piece of fabric or cloth which the device constituting this invention is adapted to produce.

Referring to the drawings in detail, and to Figures 1 to 4, inclusive, in particular, it

will be seen that the reference numeral 1 designates the frame of a conventional loom having the breast beam 2 mounted thereon and the lay 3 also mounted thereon for 5 swinging movement in a vertical plane in the usual manner.

Rigidly mounted on the upper side of the beam 2 adjacent the opposite end thereof and extending transversely thereon is a pair of 10 tubular brackets 4 having slidably mounted therein the horizontally disposed elongated bars 5 which are circular in cross section and the opposite ends of which project outwardly from the opposite ends of the brackets 4 and 15 best illustrated in Figure 2 of the drawings.

The inner ends of the arms or rods 5 have formed integrally thereon the transversely disposed bearing eyes or sleeves 6 for rotatably receiving the pintles 7 which project 20 longitudinally from the opposite ends of an elongated knitted needle supporting bed plate 8 which is best mounted for oscillatory movement on the rods 5.

The upper side of the bed plate 8 is provided with a series of spaced parallel, transversely extending grooves or channels 9 the depth of which is progressively increased from the inner edge of said bed plate to the outer edge thereof, as illustrated to advantage in Figures 5 and 6 of the drawings. Disposed on the bed plate 8 within the channels 9 thereof are the knitting needles 10 having the intermediate vertically offset portions 11 which are adapted to fulcrum on the inner edge of the bed plate 8, the outer end portion of the needles being adapted for vertical swinging movement in the channels 9. The inner end of each knitting needle 10 is provided with the hook 12 which is closed 40 by a pivoted latch 13. The outer end of each of the knitting needles 10 is formed to provide an upstanding integral yoke 14. A cover plate 15 is mounted across the upper side of the bed plate 8 in a manner to retain 45 the knitting needles 10 in position in the channels 9. As clearly seen in Figure 5 of the drawings, the upper end portions of the yokes 14 are adapted to be projected above the horizontal plane of the cover plate 15.

Rigidly connected to the bed plate 8 adjacent one end thereof and extending outwardly therefrom is an arm 16 which, as seen in Figure 9, has a roller 17 journaled on one side of its free end portion adapted to travel 55 in a cam groove 18 formed in one side of a block 19 which is mounted on the upper side of the plate 2 adjacent one of the brackets 4.

Referring again to Figure 2 of the drawings, it will be seen that a pair of oppositely 60 extending levers 19' having the beveled outer longitudinal edges 20 are hingedly mounted, as at 21, on the upper side of the cover plate 15 and said levers are adapted for swinging movement in a horizontal plane transversely 65 and slidably on said cover plate 15. The

pintles 7 of the bed plate 8 project outwardly beyond the bearing sleeves or eyes 6 on the rods 5 and mounted on the projecting free end portions of said pintles are the double ended levers 22 which are adapted for oscillatory movement on the pintles and provided with a longitudinally extending slot 23 in their upper ends for operatively connecting said levers 22 to the levers 19' through the medium of the pins 24 which project from the outer ends of said levers 19'. The lower end portions of the levers 22 are provided with longitudinally extending slots 25 for slidably receiving a pin 26 which projects from the free end portion of each of a pair of stationary brackets 27 which is mounted on the inner side of the beam 2 of the loom.

A pair of brackets 28 is mounted on the outer side of the breast beam 2 adjacent the opposite ends thereof and extending outwardly and downwardly therefrom and have journaled through their free end portions the horizontally disposed elongated shaft 29 having the upstanding arms 30 fixed thereon provided with the longitudinally extending slots 31 in their free end portions for slidably receiving the pins 32 which project laterally from the outer end portions of the rods 5 in a manner to operatively connect said arms 30 to said rods 5. A depending arm 33 is fixed on one end portion of the shaft 29 and a rod 34 operatively connects said arm 33 with the upper end portion of a lever 35 which is pivotally mounted at an intermediate portion thereof as at 36 to the bar 37 which constitutes a part of the frame 1 of the loom. The lower end of the lever 35 is engaged with a cam 38 which, in turn, is fixed on one end portion of a power shaft 39 which is journaled for rotation in the frame 1 in the usual manner. As will be apparent, the lever 35 is actuated by the cam 38. Any suitable means may be provided for maintaining the lever 35 constantly in engagement against the cam 38. It is further understood, of course, that the power shaft 39 is operatively connected to the driving mechanism of the loom for actuation thereby in the usual manner.

Cam wheels 40 having cam grooves 41 formed therein are fixed in longitudinally spaced relation on intermediate portions of the power shaft 39 for operative engagement with the levers 42 which are mounted for swinging movement, as at 43 on the loom frame 1 and said levers 42 are operatively connected with the lay 3 through the medium of the links 44.

As will be seen in Figure 11 of the drawings, the reference numeral 45 designates the warp threads of a piece of fabric or cloth which has been produced by this device, the numeral 46 designates the weft threads which have been knitted and 47 designates the weft threads which are left unknitted.

In operation, the bed plate 8 with the needles 10 mounted in position thereon is moved in and out in a horizontal plane on the supporting rods 5 through the medium of the arms 30, the shaft 29, the depending arm 33, the connecting rod 34, and the lever 35 which is actuated by the cam 38 fixed on the power shaft 39. The cam 38 is of a configuration to move the needles 10 inwardly and then outwardly only after every other or every second passage of the loom shuttle (not shown) through the shed. By reason of this arrangement, the needles 10 engage every second weft thread which is left by the shuttle as will be understood. As the bed plate 8 moves inwardly and as the needles 10 approach the weft thread which has just been left by the shuttle, the arm 16 is swung upwardly by the cam groove 18 in a manner to rock the bed plate and cause the inner end of the needles to swing downwardly and dive beneath the weft thread. It is understood that the latch 13 is in open position when the needles 10 are at this point of their travel, as indicated in Figure 5 of the drawings. When the needles 10 have passed beneath the weft threads, the roller 17 on the arm 16 will have reached the innermost portion of the cam groove 18 and said arms are allowed to swing downwardly in a manner to shift the bed plate and raise the hooked end portions 12 of the needles into engagement with the weft threads and the bed plate with the needles thereon then starts its return movement.

The needles with the weft threads carried thereby then move back to the beat-up point and the lay 3 then comes forward to the beat-up point and returns to its inoperative position. The second weft thread is then left by the shuttle returning to its starting point and this thread is not knitted by the needles but is carried to the beat-up point by the lay 3 in the usual manner and binds a preceding weft thread which has been knitted in the cloth or fabric. As the needles move to the beat-up point the same are swung downwardly by the arm 16 moving upwardly in the cam groove 18 and said needles will be at their lowermost point when they reach the beat-up point. The needles are then raised by the arm 16 in a manner to form the loops 48 in the weft threads 46, (see Figure 11) and said weft threads are released from the needles, and the loops are closed by the next knitting operation.

As before stated, the weft thread as thrown by the shuttle, is not knitted on every throw but is knitted on every other throw, one weft thread being left unknitted and used to bind the knitted thread in the warp.

In order that the weft thread will be the same distance from the beat-up point at both sides of the loom at the same time that the needles come forward to catch the threads,

it is necessary that the lay 3 move forward in a manner to even the threads and this movement is accomplished by reason of the configuration of the cam grooves 41 in the cam wheels 40 which are designed to move the lay forward just far enough to even the weft threads across the loom with every other throw of the shuttle and after which the lay returns to its inoperative position. This partial movement of the lay takes place only during a knitting operation and after the shuttle has left a thread which is to be knitted.

In order that there will be no slack in the weft thread after the needles have caught the same when knitting wide cloth or fabric on a large loom, it is necessary that any slack which may be present be taken out of the weft thread after the same is engaged by the needles. This is accomplished by means of the levers 19' having the beveled outer edges 20 which, as the bed plate 8 moves outwardly, are swung outwardly on the pivotal connection 21 through the medium of the double ended levers 22 which are rocked on the pintle 7 through the medium of the stationary brackets 27 and the pins 26 which project therefrom. As the needles move inwardly toward the beat-up point the levers 19' engage the yoke portion 14 of said needles successively from the innermost of said needles toward the outermost thereof and this operation causes the needles to fulcrum on the bed plate 8 in a manner to swing the hooked end portion thereof upwardly and draw the weft thread therein taut. It will thus be seen that this movement begins at the center of the bed plate and works toward the opposite ends thereof at the same time.

It is believed that the many advantages of a means for producing a combined woven and knitted fabric in accordance with this invention will be readily understood, and although the preferred embodiment of the invention is as illustrated and described, it is to be understood that changes in the details of construction may be had which will fall within the scope of the invention as claimed.

What is claimed is:—

1. Means for producing a combined woven and knitted fabric comprising a pair of rods slidably mounted on a support, a bed plate pivotally mounted for oscillatory movement between the rods, a plurality of needles fulcrumed for swinging movement in a vertical plane on the bed plate, means for sliding the rods in a horizontal plane, means for oscillating the bed plate on the rods, said rods and bed plate actuating means adapted to engage the needles with weft threads which have been left by the loom shuttle and being further adapted to actuate said needles in a manner to knit the weft threads and means for shifting the needles in a vertical plane on the bed plate in a manner to remove slack

- from the weft threads when the same is engaged by the needles.
2. Means for producing a combined woven and knitted fabric comprising a pair of horizontally slidable rods, mounted on the breast beam of a loom, a bed plate mounted for oscillatory movement between the rods and having a series of transversely extending inclined channels in its upper side, a series of needles fulcrumed for vertical swinging movement in the channels, means for sliding the rods in a horizontal plane, a cam mounted on the breast beam of the loom, means operatively connecting the bed plate to the cam in a manner to oscillate said bed plate on the rods upon shifting movement of said rods and the bed plate in a horizontal plane, said needles engageable with weft threads left by the loom shuttle and adapted to form the same into knitting and means mounted on the bed plate for swinging the needles in a vertical plane thereon in a manner to tighten the weft threads which are engaged with the needles prior to the knitting of said weft threads.
3. In a loom having shedding mechanism and weft inserting mechanism, the combination with said mechanisms of means for producing a combined woven and knitted fabric comprising a supporting structure and a needle mounted for compound movement on the supporting structure, said needle being operatively engageable with weft threads left by the weft inserting mechanism for knitting said weft threads.
4. In a loom having shedding mechanism and weft inserting mechanism, the combination with said mechanisms of means for producing a combined woven and knitted fabric comprising a supporting structure mounted on the loom, needles mounted for compound movement on the supporting structure, said needles being operatively engageable with certain of the weft threads left by the weft inserting mechanism for knitting said weft threads, and means for actuating the needles.
5. In a loom having shedding mechanism and weft inserting mechanism, the combination with said mechanisms of means for producing a combined woven and knitted fabric comprising a supporting structure mounted on the loom, needles mounted for compound movement on the supporting structure, said needles being operatively engageable with certain of the weft threads left by the weft inserting mechanism for knitting said certain weft threads, and means operatively connecting the needles to the loom for actuation thereby.
6. In a loom having shedding mechanism and weft inserting mechanism, the combination with said mechanisms of means for producing a combined woven and knitted fabric comprising a supporting structure mounted on the breast beam of the loom, needles mounted for simultaneous horizontal move-
- ment and vertical swinging movement on the supporting structure, said needles being operatively engageable with certain of the weft threads left by the weft inserting mechanism for knitting said certain weft threads, and means operatively connecting the needles to the loom for actuation thereby.
7. In a loom having shedding mechanism and weft inserting mechanism, the combination with said mechanisms of means for producing a combined woven and knitted fabric comprising a supporting structure and a needle mounted for compound movement on the supporting structure, said needle being operatively engageable with weft threads left by the weft inserting mechanism for knitting said weft threads, and means for rocking the needle in a manner to remove slack from the weft thread which is engaged by said needle.
8. In a loom having shedding mechanism and weft inserting mechanism, the combination with said mechanisms of means for producing a combined woven and knitted fabric comprising a supporting structure, needle supporting means mounted for simultaneous sliding and rocking movement on the supporting structure, needles mounted on the second named means, and means for actuating the said second named means.
9. In a loom having shedding mechanism and weft inserting mechanism, the combination with said mechanisms of means for producing a combined woven and knitted fabric comprising a needle supporting member mounted for simultaneous sliding and rocking movement on a supporting structure, needles swingably mounted on the member, said needles being operatively engageable with weft threads left by the weft inserting mechanism for knitting said weft threads, means for actuating the member, and means for rocking the needles on the member in a manner to remove slack from the weft thread which is engaged by the needles.
10. In a loom having shedding mechanism and weft inserting mechanism, the combination with said mechanisms of means for producing a combined woven and knitted fabric comprising a needle supporting member mounted for simultaneous sliding and rocking movement on a supporting structure, needles swingably mounted on the member, said needles being operatively engageable with weft threads left by the weft inserting mechanism for knitting said weft threads, means for actuating the member, and means for rocking the needles on the member in a manner to remove slack from the weft thread which is engaged by the needles, the last named means comprising a lever pivotally mounted on the member and operatively engageable with the needles, and a lever connected to the member for actuation thereby.

and with the first named lever for operating same.

11. Means for producing a combined woven and knitted fabric on a loom having shedding mechanism and weft inserting mechanism, comprising in combination with said mechanisms, a supporting structure, needles shiftably mounted on the supporting structure and operatively engageable with weft threads left by the weft inserting mechanism for knitting said weft threads, and means for actuating the needles.

12. In a loom having shedding mechanism and weft inserting mechanism, the combination with said mechanisms of means for producing a combined woven and knitted fabric comprising a supporting structure and a latch needle mounted for compound movement on the supporting structure, said needle being operatively engageable with weft threads left by the weft inserting mechanism for knitting said weft threads.

In testimony whereof I affix my signature.
